L. E. MORRISON

PRINTING PRESS

Filed Aug. 14, 1924

Fig. 4
Lewis E. Morrison Inventor
By his Attorney
Ivan E. O. Griswold

UNITED STATES PATENT OFFICE.

LEWIS E. MORRISON, OF NEWARK, NEW JERSEY, ASSIGNOR TO KLYMAX FEEDER COMPANY, A CORPORATION OF NEW JERSEY.

PRINTING PRESS.

Application filed August 14, 1924. Serial No. 731,945.

To all whom it may concern:

Be it known that I, LEWIS E. MORRISON, a citizen of the United States, and resident of Newark, in the county of Essex and State 5 of New Jersey, have invented certain new and useful Improvements in Printing Presses, of which the following is a specification.

This invention relates to printing presses, 10 and the object of the invention is to improve certain parts of the mechanism for transferring the paper to the platen disclosed in my U. S. Letters Patent Number 1,393,036 dated October 11, 1921.

Accordingly, my invention is embodied in a mechanism for the purpose set forth and arranged as hereinafter described and as illustrated in the accompanying drawing in which—

20 Fig. 1 is a side view of the paper transferring mechanism of an automatic job press with parts omitted and broken away.

Fig. 2 is a development in plan view of certain of the parts shown in Figure 1.

25 Fig. 3 is a detail view showing a modification.

Fig. 4 is another detail view showing a still further modification of the device.

As disclosed in the said patent, the improvement relates to an automatic job press 30 of the type known as a Chandler & Price job press, and concerns the means for automatically transferring the paper to the platen after the paper or sheet has been separated 35 from the pile.

Reference is hereby made to the said patent for a more full and detailed disclosure of the invention. The particular mechanism referred to is called in said patent a transferring mechanism and consists of a hinged table or frame which receives the single separated sheet and from which frame the sheet 40 is thereafter run off onto the platen.

The frame is hinged to a paper supporting 45 table, which in turn is hinged to the press so as to be raised away from the press or lowered into operative relationship with the press mechanism. When the paper supporting and other mechanisms, including the 50 transferring frame, are raised, they may be swung to one side of the press so that the latter may be hand fed or for other purposes.

This raising and lowering feature is to be considered in connection with the present in-

vention. In the said transfer table there is 55 provided a shaft which is rotated and over which and in contact with which the sheet of paper is run off onto the platen. The particular object of this invention is to provide novel and improved means for rotating the 60 said shaft.

Referring to the drawing, the frame of the press is marked 3 and the platen 6, pivoted to the frame at 5. The paper 52 rests on a paper support 41 mounted on the feed table 24. The latter is pivoted at 21 to a suitable bracket 22. By means of levers 28 and 31 the feed table 24 may be raised from the normal position shown in full lines in the drawing to the elevated position shown in dotted 70 lines.

The transfer table is represented by an arm 83 pivoted to the feed table at 81 and carrying the shaft 84, it being understood that there is an arm 83 on each side of the 75 press and that the shaft 84 extends from the one side to the other.

All of the above-described parts are identical with the same parts disclosed in the said patent, and as a matter of reference, the 80 numerals used in this specification to identify said parts are similar to those used in the said patent.

As shown in Figure 1 herein, the separated sheet of paper 4 drops on the transfer 85 table 83 and as the shaft 84 rotates, it causes the sheet to be run off onto the platen. The shaft 84 is driven from the usual platen locking cam 12, which is well known in the art.

Referring to Figures 1 and 2 it will be 90 seen that the shaft 84 is extended outside the part 83 and carries a pulley 7. The aforesaid pivot 81 is in the form of a rod which extends parallel to the shaft 84. On the end of said rod 81 there is mounted a double 95 pulley 8-9 with a space between the two pulleys 8 and 9, and on the hub 10 of said double pulley is pivoted an arm 11 which is free to swing on said hub 10.

The lower, free, end of the arm 11 carries 100 a larger pulley 13 to which is suitably secured a driving wheel 14. A belt 15 runs over the pulleys 7 and 8, and another belt 16 runs over the pulleys 9 and 13.

The driving wheel 14 is arranged to be 105 held in driving contact with the cam 12 to be driven from the latter, and if found necessary, both the wheel and a portion of

said cam may be provided with meshing grooves 17 and 18 for better driving contact.

From the foregoing it will be clear, that when the press is operating, the shaft 84 will be rotated to run off the sheets to the platen. Again it will be observed, that when the paper feed table is raised as shown in Figure 1, the transfer table 83 and the arm 11 may be swung upwards in over the feed table 24 and rest there and these parts then do not obstruct any other parts of the press, nor interfere with making ready, hand feeding or other operations.

Means are provided for obtaining automatic frictional driving contact between the driving wheel 14 and the cam 12. On one side of the press, the paper feed table 24 carries a pin 20 which enters a socket in a standard 25 and thus supports the table 24 when it is lowered. On said standard 25 there is mounted a plunger 26 which is urged towards the platen by a spring 27. The arm 11 is provided with a bearing surface 29 forming a notch as shown.

With the press operating automatically, the parts are in the position shown in full lines in Figure 1 and it will be seen that the spring pressed plunger 26 presses the driving wheel 14 into good driving, yet yielding, contact with cam 12. When the arm 11 is lowered from the position shown in dotted lines in Figure 1 (or lowered from the same position on an already lowered feed table 24), the extreme end of the arm comes into contact with the end of the plunger 26, and as the arm 11 slides into position, the plunger automatically engages the bearing surface 29 as will be understood.

The arrangement shown in Figure 3 indicates a coiled spring 32, the end 33 of which presses against the arm 11. The spring is coiled around the rod 81.

In the arrangement shown in Figure 4, the plunger 34 may be pulled away from the arm 11 by means of a knob 35. In this case the plunger is formed with a finger 36 which engages the arm.

If desired the arm 11 may be swung upward into the position shown in dotted lines in Figure 4 and rest on a small laterally sliding member or latch 40.

It has been found that with the mechanism herein disclosed, a positive drive is obtained for the transfer table shaft 84. That the several parts are quickly moved out of the way when it is desired to gain access to

the press parts immediately adjacent thereto.

I claim:

1. The combination of a press, a rotatable disk thereon, paper transferring means, a shaft in the same, a double pulley carried on said transferring means, a belt for driving said shaft from one of said pulleys, and means pivoted on said transferring means and in frictional driving contact with the said disk for driving the other of the said double pulley.

2. The combination of a press, a rotatable member thereon, paper transferring means, a shaft in the same, means for driving said shaft from the said member comprising a plurality of pulleys and belts for driving the same, a wheel held in frictional driving contact with said rotatable member, said wheel being arranged to drive one of the said pulleys.

3. The combination of a press, a rotatable member thereon, paper transferring means, a shaft in the same, means for driving said shaft, a double pulley on said transferring means, a belt for driving the said shaft pulley from one of the double pulleys, an arm loosely pivoted on said transferring means, a pulley and drive wheel on said arm, a belt for driving the other of said double pulleys from the pulley on the said arm and means for holding said wheel in frictional driving contact with said rotatable member.

4. The combination of a press, a rotatable member thereon, a paper feed table, paper transferring means, a rod for pivoting the latter on said paper feed table, a shaft in said transferring means, a pulley on said shaft, a double pulley mounted on the said rod, a belt for driving the first named pulley from said double pulley, an arm pivoted on said double pulley, a pulley and driving wheel on said arm, a belt for driving the double pulley from said last named pulley and automatic operated means for holding said driving wheel in contact with the said rotatable member to be driven therefrom.

5. The combination of a press, a paper feed table, a rotatable member on said press, paper transferring means, a shaft in the same, mechanism for driving said shaft from the said rotatable member, said mechanism being arranged to be swung upwards away from said rotatable member and brought to rest on the said paper feed table.

LEWIS E. MORRISON.
